UNITED STATES PATENT OFFICE

2,234,529

ERASER AND CHALK RAIL CLEANER

John C. Mather, Indianapolis, Ind.

Application August 11, 1938, Serial No. 224,295

5 Claims. (Cl. 15—12)

This invention relates to a blackboard eraser and chalk rail cleaner construction.

This invention is an improvement upon my prior invention represented by Patent No. 1,985,939 dated January 1, 1935.

The invention herein embodies certain features which are of a corrective character in connection with the patented invention referred to, or extends the range of use of the device of said patented invention, or provides a more portable arrangement, the latter being inherently required for chalk rail cleaning purposes.

The chief object of the invention is to provide a combination chalk rail and eraser cleaner structure having the foregoing characteristics.

The chief feature of the invention consists in the form of the device embodying the invention as hereinafter set forth, whereby the several objects are accomplished.

Other objects and features of the invention will be set forth more fully hereinafter.

The full nature of the invention will be understood from the accompanying drawing and the following description and claims:

In the drawing, Fig. 1 is a top plan view of the invention arranged for chalk rail cleaning.

Fig. 2 is a vertical sectional view taken on line 2—2 of Fig. 1 and in the direction of the arrows.

Fig. 3 is a perspective view looking toward the front and inside of the eraser cleaning suction aperture closure.

Fig. 4 is a perspective view looking toward the inside of the chalk rail suction aperture closure cap.

In the drawing, 10 indicates a metal base having an upright portion 11 suitably secured in the present instance at 12 to a fan housing 13. The base portion may be provided with rubber feet 14 or any other cushioning or silencing support.

Secured to the fan housing 13 is a motor housing 15 and secured to it at opposite ends, as indicated at 16 more particularly, is a U-shaped handle 17, the latter being apertured to permit the entrance of a flexible electric cable structure

13 connected to a motor, not shown, within the housing 15 and controlled by a switch having the exposed handle portion 19 carried by said housing 15. The current supplying cable structure terminates in the accessory plug terminal structure 20 for wall receptacle connection.

The motor includes a shaft 21 that extends beyond the motor housing 15 and into the fan chamber 22. Mounted thereon in any suitable manner is a fan structure 23. The chamber 22 has an outlet arrangement 24 which is adapted

to detachably support a usual collecting bag structure 25. The detachable arrangement is provided so that the chalk and debris collected from the erasers and/or the chalk rails may be removed from the bag from time to time as desired or required.

The fan housing 13 includes an intake opening 26 which communicates with chamber 27 in the housing 28, the latter including a flange 29 by which the portion is secured as at 30 to the fan 10 housing. As illustrated clearly in Figs. 1 and 2, the upright portion 11 by its mounting simultaneously secures these two parts together as well as serves as the connection between the rest or platform portion and the cleaning portion of the 15 device.

The housing 28 includes a downwardly directed duct extension 31 which for eraser cleaning is normally closed by a frictionally mounted metallic cap 32. When eraser cleaning is not desired 20 but chalk rail cleaning is desired, this cap—see Fig. 4—is removed and a flexible conduit 33 is detachably associated with the open end of the duct structure.

The opposite end of the conduit 33 terminates 25 in a suction mouth indicated generally by the numeral 34 which may be detachably associated with the end of the conduit 33 or telescopically connected thereto. Preferably this suction mouth is made of fairly flexible rubber so that it can 30 be readily manipulated at the same time that it is being guided and by the same hand so that the suction may be applied locally as desired or required.

This suction mouth has an opening 35 substantially at right angles to the opening that receives the end of the conduit 33. The suction mouth is shown substantially elliptical and having a relatively large major axis as compared to its minor axis whereas the opposite opening 40 for conduit reception is substantially circular in outline.

It is quite obvious that when the motor is actuated by closing the switch indicated by the numeral 19, and the fan rotates, that very much 45 suction will be applied to the opening 35. This is because the chamber 27 has an upwardly directed opening arrangement similar to the mouth or throat in the before mentioned patent, and through which is exposed the beater for 50 eraser cleaning.

The present invention, therefore, contemplates the addition of a cover cap for this beater exposing aperture. Said cover cap is shown clearly in Fig. 3. It is also illustrated in top plan and 55

in central section in Figs. 1 and 2, respectively. It includes the main body portion 36, the upwardly and arcuately directed portion 37 and the rim portion 38. The rim portion is only 5 around three sides of the body portion. The rim portion is recessed as at 39. The opposite edge of the body portion has a suitable conformation, as indicated by the numeral 40. The purposes of the aforesaid are as follows:

- 10 The recess at 39 is to provide clearance for the extension 41 which forms a bearing for the shaft 42 which may be integral with or an extension upon the motor shaft 21, or the fan shaft if these parts be detachably associated 15 together. The conformation 40 conforms to the exterior outline, indicated by the numeral 43 in Fig. 1, of the anchoring flange portion 29 of the housing 28. The heater housing 28 is secured to the fan housing 31 by flange 29 and members 20 12-30. It will be apparent that when the motor is energized and the fan is actuated that no air can enter the chamber 27 when the cover cap shown in Fig. 3 is properly positioned, except that which enters through the duct 31 and, 25 therefore, the full suction effect of the fan is available for chalk rail cleaning.

Reference now will be had more especially to Figs. 1 and 2 wherein a certain guard feature arrangement is provided. In the use of the invention as described in the beforementioned patent, there was danger of the school children inadvertently having their small fingers engage in the opening through which was exposed the beater structure and in some instances the fingers 30 35 were injured by the spiral blades of the beater structure mashing the finger tips against the wall of the opening.

In the present invention the spiral blades of the beater structure are shown serrated; in other 40 words relieved. Herein the beater structure is indicated—see Fig. 2—by the numeral 50, the vanes thereon by the numeral 51 and the relief or recessing by the numeral 52. The opening through which these vanes are successively exposed for engaging the lower surface of the eraser for beating purposes, all the while, however, being subject to suction, is indicated by the numeral 53. This opening in the present form of the invention is now provided with 45 50 guard means in the form of integral extensions or ribs 54 which extend from one side of the opening 53 to the opposite side and in the slots formed thereby, the several teeth portions of the vanes are successively exposed for beating 55 purposes.

It will be quite obvious, therefore, it is now impossible for children to have their fingers caught between the vanes of the beater and the side wall of the opening 53 in the eraser cleaning 60 operation.

It will of course be obvious that for eraser cleaning the cover cap shown in Fig. 3 must be removed. In order to secure the full effect of suction on the eraser being cleaned and at 65 the same time beaten, the conduit 33 preferably should be detached in place of being closed and for this purpose, as previously stated, the metallic cap 32 is provided for the free and open end of the duct portion 31.

70 It will also be apparent that the so-called guard or rib portions 54 upon the application of suction to the chamber 27 when the device is to be used for chalk rail cleaning, prevent the cover cap portion 37—see Fig. 3—from being 75 sucked into the opening 53.

While the invention has been illustrated and described in great detail in the drawing and foregoing description, the same is to be considered as illustrative and not restrictive in character.

The several modifications which will readily suggest themselves to persons skilled in this art, all are considered to be within the broad scope of the invention, reference being had to the appended claims.

The invention claimed is:

1. In a suction cleaner suitable for eraser cleaning, the combination with a chamber subject to a source of suction and having an upper, eraser supporting face with an elongated aperture therein, and an elongated rigid member in said chamber and with longitudinally directed rigid rib means thereon movable into and out of the aperture in the rotation of said member, of guard means of rib like character extending 15 across the aperture, the rib means having recesses therein coincident with the guard ribs, the rib means intermediate the recesses projecting upwardly between the guard means and above the plane of the supporting face for eraser contact in the rotation of said member.

2. In a suction cleaner suitable for eraser and chalk rail cleaning, the combination with a fan chamber, a beater chamber axially aligned therewith and having axial communication therewith a motor driven fan in the fan chamber, and an elongated eraser beater in the beater chamber and axially aligned with the fan and connected thereto, the beater chamber having an elongated aperture for beater and eraser engagement, of 30 a suction intake conduit communicating with the beater chamber immediately adjacent the communication of the beater chamber with the fan chamber, closure means for closing said intake, and other closure means for closing the aperture 40 and arranged for beater clearance, the first mentioned closure means being utilized in eraser beating operation and said other closure means being utilized in intake utilization, the intake communicating with the second mentioned 45 chamber diametrically opposite the beater accommodating aperture therein.

3. In a suction cleaner suitable for eraser and chalk rail cleaning, the combination with a fan chamber, a beater chamber axially aligned therewith and having axial communication therewith, a motor driven fan in the fan chamber, and an elongated eraser beater in the beater chamber and axially aligned with the fan and connected thereto, the beater chamber having an elongated 50 aperture for beater and eraser engagement, of a suction intake conduit communicating with the beater chamber immediately adjacent the communication of the beater chamber with the fan chamber, closure means for closing said intake, 55 and other closure means for closing the aperture and arranged for beater clearance, the first mentioned closure means being utilized in eraser beating operation and said other closure means being utilized in intake utilization, the intake 60 being a substantially elongated passage inclined outwardly and at an angle less than an obtuse angle between the beater-fan axis and the intake inclination.

4. In a suction cleaner suitable for eraser and 70 chalk rail cleaning, the combination with a fan chamber, a beater chamber axially aligned therewith and having axial communication therewith, a motor driven fan in the fan chamber, and an elongated eraser beater in the beater chamber 75

and axially aligned with the fan and connected thereto, the beater chamber having an elongated aperture for beater and eraser engagement, of a suction intake conduit communicating with the beater chamber immediately adjacent the communication of the beater chamber with the fan chamber, closure means for closing said intake, and other closure means for closing the aperture and arranged for beater clearance, the first mentioned closure means being utilized in eraser beating operation and said other closure means being utilized in intake utilization, the intake being an elongated passage inclined outwardly, the intake communicating with the second mentioned chamber diametrically opposite the beater accommodating aperture therein.

5. In a suction cleaner suitable for eraser and chalk rail cleaning, the combination with a fan chamber, a beater chamber axially aligned therewith and having axial communication therewith, a motor driven fan in the fan chamber, and an

elongated eraser beater in the beater chamber, and axially aligned with the fan and connected thereto, the beater chamber having an elongated aperture for beater and eraser engagement, of a suction intake conduit communicating with the beater chamber immediately adjacent the communication of the beater chamber with the fan chamber, closure means for closing said intake, and other closure means for closing the aperture and arranged for beater clearance, the first mentioned closure means being utilized in eraser beating operation and said other closure means being utilized in intake utilization, spaced guard means extending across the beater aperture, and rigid, longitudinally directed rib means on the beater, the rib means having recesses therein coincident with the guard means, the rib means intermediate the recesses projecting upwardly between the guard means for eraser contact in the rotation of the beater.
